UNITED STATES PATENT OFFICE

2,684,706

STOCK STRAIGHTENER

John H. Friedman, Tiffin, Ohio, assignor to The National Machinery Company, Tiffin, Ohio, a corporation of Ohio

Application July 9, 1949, Serial No. 103,871

3 Claims. (Cl. 153—32)

1

This invention relates to apparatus for straightening the end portion of coiled rod, bar or wire stock.

Many high-production machines and machine tools such as forging machines, heading machines, screw machines, and turret lathes work or fabricate pieces from rod, bar, or wire stock, and in some instances such stock is received in coiled form and fed into the machine. Certain of these machines rely upon feed tubes to receive and straighten the stock, and others may be fitted with auxiliary stock straightening devices that continuously straighten the stock until the coil is exhausted, an example of the latter type of apparatus being disclosed in the patent to Friedman, 2,219,811. Regardless of whether the metal-working machine is provided with a straightener as shown in the aforesaid patent or whether it is merely provided with a feed tube that straightens the stock as it is consumed, when coiled stock is provided it is usually necessary that the initial or free-end portion of the coiled stock be straightened before it is fed to the machine. It has been customary to hand straighten the free end of such coiled stock, but this is a time-consuming operation, it may not produce perfectly straight stock, and when large diameter rod is employed the operation is difficult to perform. The problem is further complicated by the fact that the larger diameter stock (the most difficult to straighten), is coiled in relatively short lengths dictated by handling and weight consideration, the result being that with heavy stock the straightening operation must be performed more often than with light stock.

A principal object of this invention is to accurately and quickly straighten an end portion of coiled stock of any diameter normally encountered by simple apparatus readily controlled by the operator.

It is a further object of the invention to provide an apparatus for straightening the end turn of a coil of stock and advancing the straightened end turn into a header without removing the coil of stock from the apparatus and to carry out such straightening and advancing operations by hydraulic means.

Further objects and advantages relating to efficient manipulation of the coiled stock and the elimination of time consuming manual operations will appear from the following description and the appended drawings wherein:

Fig. 1 is a plan view, with parts broken away, showing the stock straightening and guiding apparatus of the invention;

Fig. 2 is a sectional view showing the stock support and the stock grip apparatus employed to align and guide the straightened free end of the stock to the header; and

Fig. 3 is an elevation with parts in section showing the apparatus for straightening the free end

2

of the coil of stock prior to advancing the same into the header.

The apparatus of the invention comprises generally a rectangular frame having a reciprocable drum carriage mounted on the frame for movement toward and away from the header or other machine for which the stock is intended. One side of the frame is provided with a stock straightening apparatus arranged to grip the free end of a coil of stock and hold the same fixed in space while the drum carriage is moved away from the gripped end so as to unwind and straighten the free end of the coil of stock. The other side of the frame is provided with a vertically and laterally adjustable grip head arranged to receive and hold the unwound and straightened portion of the stock and move the same into alignment with the opening in the header or other machine using the stock. The apparatus includes a hydraulic system having valves and cylinders arranged to effect movement of the parts of the apparatus so as to carry out the gripping, straightening and advancing operations.

Referring to the drawings, the frame indicated at F in Fig. 1 comprises a pair of I beams 10 spaced from each other and arranged generally in alignment with the feed opening in the header or other machine (not shown). A carriage, indicated generally at C, is mounted to move longitudinally of the frame by means of rollers 12 pivoted on the carriage at each corner thereof and arranged to ride on the horizontal flanges of the I beams 10—10. Rollers 11, carried at each corner of the carriage, are pivoted thereon on vertical axes and are arranged to bear against the web portions 10a of the I beams so as to guide the carriage laterally in its travel. At one end of the frame F (right-hand end in Fig. 1), a frame cross member 10b is provided with longitudinally extending channels 17 arranged to support a transverse pin 17a on which is pivoted, by means of brackets 16, a hydraulic cylinder 13. The cylinder 13 is a double-acting hydraulic cylinder and the piston rod 14 thereof is secured to the carriage C so that actuation of the hydraulic cylinder 13 moves the carriage C toward and away from the header or other machine using the stock.

The carriage C includes (as shown in Fig. 2) a platform 18 upon which is mounted a pedestal 19 having a horizontal flange or table 19a that is centrally apertured to receive a vertically disposed pintle 20a of the stock drum support 20. The drum support 20 has fixed thereto a pair of spaced bosses 21 to receive the drum support shaft 22 which projects transversely of the frame to support the stock drums D and D-1. The stock support drums are each provided with an inside flange 27 adjacent the bosses 21 and are so proportioned with respect to the diameter of the stock coil that the inner end of the stock coil

bears against the flange 27 and the axis of the stock coil is maintained parallel with the supporting shaft 22 even though the diameter of the stock coil greatly exceeds the diameter of the supporting drum as illustrated in Fig. 3.

To facilitate the mounting of a stock coil on the drum, the retaining pins 23 at the outer end of the drum are mounted so as to be turned 90 degrees and pocketed inside of the drum. Pivoted brackets 24 slidably receive the pins 23 and an expansion spring 25 is placed about the inner end of each of the pins 23 and is retained on the end of the pin 23 by nut or the like 23a. The bracket 24a is apertured as at 24b in alignment with a pin slot in the drum to receive a reduced inner end portion of the pin 23. The pin 24, being slidably held in the bracket 24, permits a limited radially outward movement of the pin 23 so as to withdraw the reduced end portion from the opening 24b and the bracket 24a. When the pin is thus released from the bracket 24a, it may be turned with the pivoted bracket 24 and slid inwardly into the pocket provided within the drum as best shown in dotted lines in Fig. 1. With all of the pins 23 thus stored within the drum a full coil of stock, such as coil W-1, may be slid axially upon the drum D-1 and thereafter the pins moved to full line position of Fig. 1 to hold the coil on the drum.

A channel 10c extends laterally from the main frame 10 parallel to the end frame member 10b and said members 10b and 10c are secured to each other by a longitudinally extending frame member 10d. A similarly disposed frame member 10e extends laterally of the main frame adjacent frame member 10b and is secured to the frame member 10d to provide a sub-frame or support for the stock straightening mechanism indicated in its entirety at S and best shown in Fig. 3. Vertically extending fixed supports 35a and 35b project upwardly from the sub-frame and support between them a pin 34 which serves as a hanger for the stock straightening mechanism S. The stock straightening mechanism includes a pair of longitudinally extending bars 31 which are secured on each side of a grooved stock-receiving member 32. A pair of vertically disposed hangers 33 are secured by welding as at 33a to the flat sides of the longitudinal members 31 and said hangers are pivotally and slidably mounted at their upper ends on the pin 34. This arrangement provides that the longitudinally extending assembly 31-32 may be swung pivotally about the axis of pin 34 within the limits and may slide transversely parallel to the axis of pin 34 so that the grooved member 32 may be disposed beneath the free end of the outside convolution of the stock coil. Thus, the position of the assembly S may be adjusted to accommodate stock coils of various axial extent.

The stock straightening mechanism includes a clamp and toggle arrangement so that the free end of the stock may be gripped in the grooved member 32. The clamp comprises a bell crank 42 which is pivotally supported, as at 43, on brackets 43a secured to the outer faces of the bars 31. One end of the bell crank 42 is arranged to bear against the upper side of the free end of the stock coil and the other end of the bell crank is pivoted to toggle link 40. The complementary toggle links 41 are pivoted to the links 40 at one end and to the members 31 at the other. The toggle arrangement 40-41 is such that when the links approach a dead center position the bell crank 42 exerts a clamping action on the

free end of the stock. The toggle links 40-41 are moved to and from their clamping position by a double-acting hydraulic cylinder 36.

With the parts arranged in position as shown in Fig. 3, the piston rod 39 is moved to the left by the hydraulic cylinder 36 so as to straighten the toggle and clamp the free end of the stock down in the groove of the member 32. Thereafter the hydraulic cylinder 13 for the carriage C is operated so as to move the carriage and the stock carried thereby to a dotted line position as shown. This causes the first turn of the coil of stock to unwind and to be partially straightened by following the grooved member 32. Thereafter the entire stock straightening assembly S may be swung bodily about the pivot 34 in a clockwise direction so as to bend the unsupported portion of the stock about the curved end 32a of the member 32. To effect the bodily swinging of the stock straightening mechanism, hydraulic cylinder 37 is employed. Cylinder 37 has one end thereof pivoted, as at 38, to a bracket 38a and the other end pivoted to the depending hangers 33. Upon actuation of the cylinder 37 in one direction, the piston rod 47, pushing through the pivotal connection 48, rocks the straightening mechanism S in a clockwise direction about the pivot point 34. After the free end of the stock is bent slightly about the end portion 32a, the cylinder 36 may be operated to move the piston rod 39 thereof in an opposite direction so as to release the toggle and clamp 42 and the cylinder 37 operated to rock the assembly S in a counter-clockwise direction, restoring it to the full line position shown. The straightened free end may then be swung upwardly and in a counter-clockwise direction with respect to the drum shaft 22 so that the free end projects away from the stock straightening mechanism S and is tangent to the upper side of the stock coil W-1.

The pivoted stock supporting table 20 is adapted to be turned with respect to the pedestal 19 and the pedestal table has a pair of tapered apertures 39a spaced 180 degrees from each other adapted to receive a tapered latch pin 28-29. After the end of the stock has been straightened as above described, the latch 28 is withdrawn and the stock table 20 turned on the pintle 28a so as to dispose the straightened end of the stock on the opposite side of the frame. A coil of stock with the end thereof thus straightened is illustrated as at W in Fig. 1.

A stock gripping assembly, indicated generally as at 64, is fixed on the carriage platform 18 substantially in alignment with the opening in the header that is to use the stock. The stock gripping head is vertically adjustable by means of the jack screw 61-62 and the upper end of the jack screw is provided with a pin 66 to provide for a limited pivotal movement of the grip head 65. The grip head is open at one side and includes a grooved member 71 on the upper overhanging portion and a spring pressed grooved member 72 therebeneath. This arrangement provides that the straightened portion of the stock, indicated in Fig. 2 as W-3, may be swung laterally, by reason of the flexibility of the stock, into the grip head between the grooved portions 71 and 72. The grip head is provided with a hydraulic jack 75 arranged to bear against the under side of the member 72 and a flexible hydraulic line 78 runs from the hydraulic jack 75 to the pedal-operated hydraulic pump 76. This arrangement provides that operation by the foot pedal 77 of the pump 76 forces hydraulic fluid into the jack 75 and thus

clamps the stock W-3 firmly between the members 72 and 71. The pump 76 also includes a release lever 79 so as to release the hydraulic pressure in the pump 75.

With the straightened stock W-3 firmly gripped in the grip head 65, the worm segment 67 carried by the lower side of the grip head is moved by the worm 68 and the crank handle 70 so as to rock the grip head about the pivot 66 and bring the free end of the stock into proper lateral alignment with the stock opening in the header. Appropriate vertical adjustment may be made by the jack screw 60-61-62 so that the straightened stock W-3 may be accurately lined up with the stock feed mechanism in the header. The hydraulic cylinder 13 for the carriage C may then be operated so as to move the carriage toward the header and thus advance the straightened stock into the feed mechanism on the header. As soon as the free end portion W-3 of the stock is in position to be engaged by the feed mechanism on the header the hydraulic control for the carriage cylinder 13 may be moved to a neutral position and thus the feed mechanism on the header will, by pulling through the stock W-3, move the carriage toward the header. As the carriage approaches the end of its travel toward the header the release 79 on the hydraulic pump is operated so as to release the grip to the hydraulic jack 75. Thereafter the worm crank 70 may be operated so as to swing the worm gear sector 67 and thus swing the grip head bodily from and free of the stock. The stock may then be unreeled from its drum support in the usual manner by means of the feed mechanism in the header.

Before the stock coil W is fully unwound a new coil may be placed upon the empty drum on the other side of the carriage. The free end of the new coil may be gripped by the stock straightening clamp and the carriage operated to straighten the end of the new coil while the first coil is still being advanced into the header. In this way the apparatus provides a straightened free end that is ready for advance to the header as soon as the first coil is fully unwound and the time required to prepare a coil of stock for machine reduced over the prior art methods.

A control valve platform V is supported on the sub-frame above the gripping and bending cylinders 36 and 37 of the straightening apparatus. The valve V-13 mounted on this platform is provided with an operating handle 56 and lines 13a and 13b. The line 13a leads to the left-hand end of the carriage cylinder 13 and the line 13b leads to the right-hand end of the cylinder 13. A control valve V-37 is provided for the bending cylinder 37 and includes a line 37a going to the left-hand end of the cylinder 37 and a line 37b going to the right-hand end of the cylinder 37. A similar valve V-36 is provided for the grip cylinder 36 and this is provided with a line 36a going to the left-hand end of the grip cylinder and a line 36b going to the right-hand end of the grip cylinder. The hydraulic system includes a fluid reservoir 53 disposed between transverse frame members at the right-hand end of the frame, a motor 50 and hydraulic pumps 51-52. When the motor 50 is energized, hydraulic fluid under pressure is directed to the valves V-13, V-36 and V-37, and the handles of the valves 56, 54 and 55, respectively, may be operated so as to direct the flow to either end of the actuating cylinders or to place the valve in a neutral position.

Although one form of the invention is shown 75

and described in considerable detail, it will be appreciated that numerous changes may be made therein within the scope of the invention defined in the following claims.

What is claimed is:

1. An apparatus for straightening coil stock comprising a frame, stock support means mounted on said frame for rotatably supporting a coil of stock, a rigid straightening member formed with an elongated surface pivotally mounted on said frame adjacent to a coil of stock on said stock support means, a clamp on said member for clamping said stock to said surface, actuator means operably connecting said stock support members and said frame arranged to cause relative movement thereof thereby uncoiling a portion of said stock, and operating means operably connecting said member and frame adapted to rotate said member around said pivot into engagement with said portion of stock thereby straightening said portion of stock along said surface.
2. An apparatus for straightening coil stock comprising a frame, stock support means mounted on said frame for rotatably supporting a coil of stock, a rigid straightening member formed with an elongated surface pivotally mounted on said frame beneath a coil of stock on said stock support means, a clamp on said member for clamping the free end of said stock to said surface, actuator means operably connecting said stock support members and said frame arranged to cause relative movement thereof thereby uncoiling a portion of said stock above said member, and operating means operably connecting said member and frame adapted to rotate said member around said pivot into engagement with said portion of stock thereby straightening said portion of stock along said surface.
3. An apparatus for straightening coil stock comprising a frame, stock support means mounted on said frame for rotatably supporting a coil of stock, a rigid straightening member formed with an elongated surface pivotally mounted on said frame substantially tangent to a coil of stock on said stock support means, a clamp on said member for clamping the free end of said stock to said surface, first fluid motor means operably connecting said stock support members and said frame arranged to cause relative movement thereof thereby moving said coil beyond said member uncoiling a portion of said stock adjacent to said member and second fluid motor means operably connecting said member and frame adapted to rotate said member around said pivot into engagement with said portion of stock thereby straightening said portion of stock.
